UNITED STATES PATENT OFFICE.

BERT C SMITH AND THOMAS H. CHANDLER, OF LONG BEACH, CALIFORNIA.

TRAFFIC SIGNAL.

Application filed June 13, 1923. Serial No. 645,163.

To all whom it may concern:

Be it known that we, BERT C. SMITH and THOMAS H. CHANDLER, citizens of the United States, residing at Long Beach, in the county of Los Angeles and State of California, have invented certain new and useful Improvements in Traffic Signals, of which the following is a specification.

This invention relates to an improved traffic signal for motor vehicles and seeks, as one of its principal objects, to provide a device of this character whereby a driver may, without exertion or inconvenience, readily signal an intention to stop or to turn either to the right or left.

The invention seeks, as a further object, to provide a device embodying a pivoted signal arm and wherein means will be provided for swinging said arm by engine suction.

Another object of the invention is to provide a device wherein the movement of the signal arm may be quickly and accurately controlled and wherein the use of springs in conjunction with the arm will be eliminated.

And the invention seeks, as a still further object, to provide a device embodying signal lights, one for each of the different signaling positions of the arm, and wherein the proper light will be energized when the signal arm is swung to any one of its signaling positions.

Other and incidental objects will appear hereinafter.

In the drawings:

Figure 1 is a perspective view showing our improved signal applied to a motor vehicle of conventional design,

Figure 2 is an enlarged sectional view, parts being shown in elevation,

Figure 3 is a detail sectional view on the line 3—3 of Figure 2, looking in the direction of the arrows,

Figure 4 is a detail sectional view on the line 4—4 of Figure 2, looking in the direction of the arrows, and

Figure 5 is a detail plan view of the control valve employed.

Figure 6 is a sectional view of the control valve.

In carrying the invention into effect, we employ a suction cylinder 10 closed at its upper end by a cap 11 and provided at its lower end portion with vertically spaced ports indicated for convenience at 12, 13 and 14 respectively. Slidable in the cylinder is

a piston 15 from which extends a piston rod 16 slidable through the cap. In mounting the signal upon a vehicle, the cylinder 10 is, as shown in Figure 1, preferably arranged at one end of the vehicle wind shield, and connecting the cylinder with the wind shield are appropriate clamps 17. Mounted upon the wind shield above the cylinder is a bracket 18 secured upon the wind shield by a clamping bolt 19 connecting the companion arms of the bracket. Journaled between said arms at their outer ends is a pulley 20 having, as shown in Figure 3, a hub 21, and extending through said hub and through the arms is a pin 22 rotatably supporting the pulley. Secured at one end to the pulley is a cable or other suitable flexible element 23, the opposite end of which is attached to the upper extremity of the piston rod 16 and formed on the pulley at one side thereof is a laterally directed annular flange 24 through which is threaded a tubular signal arm 25 which will normally gravitate downwardly to vertical position for rotating the pulley and elevating the piston within the cylinder 10. Threaded upon the arm 25 at its outer end is a sector-shaped lamp casing 26 in which are mounted signal lamps indicated for convenience at 27, 28 and 29, respectively. Mounted upon the flange 24 of the pulley 20 are contacts 30, 31 and 32, the pulley with its flange being formed of fiber or other suitable insulating material, and connecting said contacts with the lamps 27, 28 and 29 are wires 33 extending through the signal arm. Mounted between the arms of the bracket 18 is a spacing block 34 receiving the bolt 19 therethrough. This spacing block is suitably insulated with respect to said bolt as well as with respect to the bracket and is formed at its lower end with a binding post 35 while at its upper end said block is provided with a spring tongue 36 bearing against the flange 24 of the pulley for engagement with the contacts 30, 31 and 32 selectively. Connected to the binding post 35 is a feed wire 37 leading from the battery or other suitable source of electrical energy upon the vehicle.

Mounted upon the steering post of the vehicle close beneath the steering wheel is a four-way control valve having a casing 38 and surrounding said casing is a clamping strap 39 connecting the valve with the steering post. Rotatable in the casing is

a tapered core 40 having an upstanding stem 41 and rotatably fitting over the upper end of the casing is a cap 42 receiving said stem therethrough. The stem is formed with a squared portion to coact with the top wall of the cap so that the cap may be rotated for turning the core and projecting from the cap is a handle 43 disposed to cooperate with a segment 44 carried by the strap 39.

10 Threaded upon the stem 41 at its upper end is a nut 45 securing the cap against upwardly displacement and bearing between the cap and the upper edge of the casing is a spring 46 holding the core seated.

15 Formed in the valve core is a passage 47 and extending between said passage and the intake manifold of the vehicle engine is a suction pipe 48 which may be connected in any appropriate manner to said manifold 20 to communicate therewith. Leading from the valve casing to the ports 12, 13 and 14 of the cylinder 10 are pipes 49, 50 and 51 and formed in the valve core to open downwardly through the lower end thereof is an 25 air inlet passage 52 which, when the valve is closed, will communicate with the pipe 51.

As will now be seen in view of the foregoing, the lever 40 of the valve may be 30 swung for establishing communication between the pipe 48 and the pipe 49, for instance, when engine suction will be communicated to the cylinder 10 at the port 12 so that the piston 15 will be drawn downwardly until the piston covers said port, at 35 which point the piston will be held by the suction. When the piston is thus drawn downwardly, the pulley 20 will, of course, be rotated and the arm 25 swung upwardly to the lowermost dotted line position indicated in Figure 1, for signaling an intention 40 of the driver to stop. Coincidentally, the contact 30 will be moved to a position beneath the tongue 36 so that the lamp 27 will be energized, assuming of course, that a 45 circuit is closed through the feed wire 37. This circuit will preferably be controlled by a suitable switch. For signaling an intention to turn to the left, the valve is opened to establish communication between the pipe 48 and pipe 50 when the piston 15 will be drawn downwardly to the level of the port 13 of the cylinder 10. This movement of the piston will serve to swing the signal arm to horizontal position when the contact 50 55 31 will be moved beneath the tongue 36 so that the lamp 28 will be energized. Similarly, for signaling an intention to turn to the right, the valve is rotated to establish communication between the pipe 48 and the pipe 51 when the piston 15 will be drawn

downwardly to the level of the port 14 of the cylinder 10. This movement of the piston will serve to swing the signal arm to the uppermost dotted line position shown in Figure 1, when the contact 32 will be moved beneath the tongue 36 for energizing the lamp 29. Thus, one of the signal lamps will be energized at each of the signaling positions of the signal arm and, preferably, the lamps will be of different color so that at night the position of the signal arm may be determined by observing the particular color of the light displayed.

After the signal arm has been swung to any one of its positions and the valve is closed, air will be admitted to the cylinder 10 through the passage 52 of the valve for relieving the partial vacuum beneath the piston 15 so that the signal arm may immediately drop.

Having thus described the invention, what is claimed as new is:

1. In a direction signal for motor vehicles, a bracket including spaced arms formed at their inner ends to embrace the frame of a windshield, a spacer interposed between the inner end portions of the arms, means extending through the arms and said spacer clamping the arms in engagement with the windshield frame, a pulley journaled between the outer ends of the arms, a signal arm mounted upon said pulley, a flexible element cooperating with the pulley, and a suction operated piston having said flexible element connected thereto and operable for 95 rotating the pulley and swinging the signal arm.

2. In a direction signal for motor vehicles, a bracket including spaced arms formed at their inner ends to embrace a windshield frame, means extending through the arms clamping the arms in engagement with said frame, a pulley disposed between the outer ends of the arms and provided with a hub elongated at one side of the pulley spacing 100 the outer ends of the arms apart, a pin extending through said hub and through the arms journaling the pulley, the pulley being formed at said side thereof with a peripheral flange overhanging the elongated portion of the hub in concentric relation, a radial signal arm fixed at its inner end to said flange, and means engaged with the pulley for rotating said pulley and swinging 105 the signal arm.

In testimony whereof we affix our signatures.

BERT C. SMITH. [L.S.]
THOMAS H. CHANDLER. [L.S.]
